UNITED STATES PATENT OFFICE.

WILLIAM E. SHARP, OF CHICAGO, ILLINOIS, ASSIGNOR TO GRIP NUT COMPANY, OF CHICAGO, ILLINOIS, A CORPORATION OF ILLINOIS.

PROCESS OF MANUFACTURING LOCK NUTS.

Application filed June 26, 1922. Serial No. 570,902.

To all whom it may concern:

Be it known that I, WILLIAM E. SHARP, a citizen of the United States, residing at Chicago, in the county of Cook and State of Illinois, have invented a certain new and useful Process of Manufacturing Lock Nuts, of which the following is a description.

My invention belongs to that general class of bolt nuts designed to so engage the operating bolt that disengagement by reason of vibration or jar is not likely to occur. It has for its object the process of producing such a nut in a practical and efficient manner, in which the product will be accurately and uniformly constructed.

In the drawings, wherein like reference characters indicate like or corresponding parts,

Fig. 1 is a plan view of the outer face 20 of the blank for such a nut;

Fig. 2 is a central view substantially on the line 4—4 of Fig. 1 before the nut is threaded or otherwise operated upon;

Fig. 3 is a section similar to Fig. 2 after 25 the initial step of the process has been taken;

Fig. 4 is a section taken substantially on line 4—4 of Fig. 1 after the nut has been threaded and the final step in its production taken;

Fig. 5 is a section on line 5—5 of Fig. 30 1 of the finished nut, and

Fig. 6 is a section substantially the same as Fig. 3, showing a modification or amplification of the first step in the process.

The preferred type of nut upon which my process is here illustrated, is that shown 35 in my United States Letters Patent Number 1,271,782, dated July 9, 1918, although the same process is to a greater or less extent applicable to the form of nut shown in the 40 companion or reverse type of nut shown in my United States Letters Patent Number 1,298,583, issued March 25, 1919, or even to the standard form of nuts.

In the drawings, 1 illustrates the body 45 of the nut, and as here described, 2 illustrates an elevated central rib on the outer face of the nut. In preparing the blanks for this type of nut it is found that there 50 is some variation in the thickness of the blank at different points; thus for illustra-

tion, the point at 3 in Fig. 2 may be higher than the point at 4 of the same figure. It is important that the deflection of the threads on opposite sides of the bolt hole 55 in nuts of this character should be substantially uniform in order to secure the greatest holding power, or engagement to prevent the nut becoming accidentally detached or disengaged by vibration. In such cases it 60 might occur that the compression, for instance at the point 3 of Fig. 2, in order to deflect the threads might cause a slight over-deflection of the thread at that point, while in attempting to obviate this the deflection at the point 4 might be under-deflected. My process has particularly in 65 mind the necessary steps to secure uniformity in this respect. This uniformity is desirable because in the formation of these 70 lock nuts, it is the effort to give them a predetermined gripping or locking power derived from the deflection or distortion of the threads. It will be appreciated that where the surfaces to be engaged by the 75 compressing means are uneven, the corresponding effect on the threads will be uncertain. Where the compression is at separated points on even or level surfaces, the effect on the thread will be uniform and 80 the desired gripping secured at opposite points. Where contrary conditions exist, however, the threads at one point may be effected to give the gripping action, whereas the threads at an opposite point, owing 85 to their less degree of compression, will not be capable of giving the maximum gripping power intended.

The first step in the process therefore 90 is to bring all of the nut blanks down to uniform thickness throughout. This I accomplish by subjecting the nut blank, before the thread is cut therein, to pressure under a suitable machine, which will bring the top surface of the nut, as shown in Fig. 3, to 95 the same plane. In the particular form of blank illustrated in Fig. 2, by this particular operation the part in proximity to the part 3 would therefore be compressed or the metal caused to flow upon itself, while, if the pressure is only sufficient to bring the blank to a uniform thickness and the outer 100

surface in the same plane, the part at the point 4 may not be modified to any particular extent. This, however, is in the simple form, as I will explain hereafter. 5 After the blank is brought to uniform thickness, as shown in Fig. 3, it is then screw-threaded in the usual manner and thereafter subjected to sufficient pressure, which being brought upon the elevated sections, as 10 is illustrated in the drawing, will cause the metal directly thereunder to flow upon itself, bringing the threads at that point closer together, to such an extent that as the nut is threaded upon its cooperating 15 bolt on the opposite face, a finger fit is secured in the first engagement of the nut, and as it is screwed home, the threads of the bolt reaching the deflected portions at 3 and 4, these threads will frictionally engage 20 the cooperating threads of the bolt to the extent that the nut is securely locked thereon in such manner as to obviate the danger of accidental disengagement by vibration or jarring. As shown in Fig. 4, 25 and based upon the explanation given of Fig. 3, the compression under the section 3 is therefore shown as greater than at the point under 4 for the reason that the part at 3 was initially compressed to bring the 30 face of the nut to the same plane. This is simply illustrated by the shading. As shown in Fig. 5, the modification of the threads directly under the elevated portion 2 by the process described is clearly indicated. 35

There is, however, a further step in the process that is available and practical, as shown in Fig. 6. The initial compression, without regard to whether the nut is of 40 uniform thickness or not, brings a compression upon the outer face of the nut so as to compress the metal on both sides of the bolt hole in immediate proximity thereto, as indicated in the shaded portions near 45 the top of Fig. 6. This is before the thread is cut in the nut, and by reason of this treatment, the nature or character of the metal on each of the elevated sections or at a plurality of points about the bolt hole, 50 is brought to a more uniform condition. The cutting of the thread thereafter and the second compression hereafter described, finishes the upper section of the nut in a more uniform manner. The second compression 55 in a nut subjected to the process last described has a tendency to deflect the threads only near the surface of the nut, that is, perhaps to a depth of two or three threads, instead of extending downward into 60 the body of the nut to a greater or less extent. This is the preferred operation, as 65 obviously the compression can be such as to cause the deflection to extend a greater distance into the body of the nut.

As I have before stated, the same process

is available in producing a nut similar to that shown in my said Letters Patent Number 1,298,583, the compression, however, working at right angles, and leading to a depression in the outer face of the nut 70 rather than to an elevation. In a nut with the usual crown face, the same process is applicable.

In the preferred form of nuts shown the reduced area subjected to pressure tends 75 to localize the deflection at those points rather than diffuse the effect of the pressure throughout the blank, and possibly to the other face of the nut which is preferably unaffected. In the form shown the pres- 80 sure is localized at a plurality of points, to-wit, at the ridge portions on the opposite sides of the bolt hole. The same is true in the reverse form mentioned, that is, at the depressed sections. 85

In the drawings the parts are necessarily exaggerated to illustrate the construction and parts.

Having thus described my invention, it is obvious that various immaterial modifications may be made in the same without departing from the spirit of my invention; hence I do not wish to be understood as limiting myself to the exact steps, form, construction, arrangement and combination 95 of parts herein shown and described, or uses mentioned.

I will not claim herein the bolt nut disclosed, as a new article of manufacture, inasmuch as the same will be presented as 100 the subject matter for a divisional application in keeping with official requirement to that end.

What I claim as new and desire to secure by Letters Patent is:

1. The process of forming a lock nut consisting in first forming the blank, then applying pressure tending to reduce the thickness of the blank, then screw-threading the nut, and again applying pressure to deflect the threads in proximity to the face of the nut. 110

2. The process of forming a lock nut consisting in first forming the blank, then applying pressure tending to reduce the 115 thickness of the blank, then screw-threading the nut and again applying pressure to the face thereof at a plurality of points to deflect the threads in proximity thereto.

3. The process of forming a lock nut consisting in first forming the blank, then applying pressure tending to reduce the thickness of the blank, then screw-threading the nut, and again applying pressure to a reduced area on one face of the nut to deflect 125 the threads in proximity thereto.

4. The process of forming a lock nut including the following steps to wit:—evening the face of a blank having an uneven surface, screwthreading the interior of the 130

blank, and applying pressure on said evened face to deflect the threads in proximity to the face.

5. The process of forming a lock nut consisting in treating a blank having an uneven surface, by applying pressure thereto to render such surface uniform, then screwthreading the nut, and again applying pressure to deflect the threads in proximity to the face of the nut. 10

In testimony whereof, I have hereunto signed my name in the presence of a subscribing witness.

WILLIAM E. SHARP.
